ELECTRIC LAMP SOCKET

Frank W. Slady, Brooklyn, N. Y., assignor to
Leviton Manufacturing Company, Brooklyn,
N. Y., a copartnership composed of Isidor
Leviton and Evser Leviton

Application June 8, 1927, Serial No. 197,261

20 Claims. (Cl. 173—362)

This invention relates to a shell and cap for housing the switch mechanism of an electric lamp socket that can be made very economically. The shell and cap can be readily connected to 5 and disconnected from each other, and are positively held in firm engagement when assembled, so that danger of longitudinal movement of the two with respect to each other, as well as danger of circumferential movement of the two with 10 respect to each other, is eliminated. The holding means to prevent longitudinal and circumferential movement of the shell and cap are so made that edges of cut metal of each contact with edges of cut metal of the other to provide 15 positive locking engagement of the two.

The invention will be understood from the description in connection with the accompanying drawing, in which Fig. 1 is a perspective view of the cap; Fig. 2 is a perspective view of the shell; 20 and Fig. 3 is a section showing the two in assembled relation with engaging portions thereof on an enlarged scale.

In the drawing, reference character 5 indicates the metal cap that is provided with a skirt 25 or flange portion 6 of the usual type. The flange or skirt portion 6 is provided with a circumferential series of inwardly projecting tongues. The tongues are made by having a series of slits 7 parallel to the edge of the flange and spaced 30 from each other, all being on the same circumferential line, with pairs of slits 8 extending from the ends of the slits 7 in an axial direction toward the edge of the cap, and terminating short 35 thereof. The tongues 9 are pushed inwardly, as indicated, with their upper ends, as well as their edges, formed of cut metal. The tongues are preferably made approximately as wide as the 40 distance between the tongues, and 20 tongues have been found to be a convenient number on the standard size cap. The metal shell 10 is of the well known type with a slot 11, that may be a key slot, extending downwardly from the 45 upper edge thereof. The upper end of the slot 11 may be widened, as indicated at 12, so as to accommodate one or more of the tongues 9. The upper edge of the shell 10 is provided with corrugations 13, equal in number to the number 50 of tongues 9 on the cap, having valleys 14 preferably slightly wider than the crests 15 in a circumferential direction. When the valleys 14 are slightly wider than the crests 15, and the 55 tongues 9 are as wide as the spaces between the tongues, each of these valleys is slightly wider than each of the tongues 9, so that the tongues 9 lie entirely within the valleys 14 when the shell and cap are assembled without necessitating the edges of the tongues resting against the edges of the crests 15. However, when the valleys and 60 crests occupy the same amount of space, the edges of the tongues are in line with the edges

of the crests when the cap and shell are assembled.

The corrugations are so disposed with relation to the widened portion 12 of the slot 11 that the edges of the space 12 terminate at 5 crests of the corrugations. In this way, cut metal edges of the shell are disposed in the circumferential path of the inwardly projecting tongues 9 so that the cut metal edges of the tongues will contact with the cut metal edges 10 of the shell to prevent relative rotation between the two, as indicated at 15' and 15'' (Fig. 3).

Horizontal slits 16 may be made in valleys 14 of the corrugations on opposite sides of the shell 10 some distance from the end thereof, and the 15 metal pressed outwardly to form projections 17 with cut metal lower ends leaving the sides and the other ends thereof integral with the remainder of the shell. The shell and cap are assembled simply by forcing the shell into the cap until 20 the lower ends of the projections 17 snap over the inwardly projecting ends of corresponding tongues 9 to prevent longitudinal motion between the shell and cap, while the edges of one or more of the other tongues contact with the outwardly 25 projecting edges of the space 12 to prevent relative circumferential motion of the two. The shell may be withdrawn simply by pressing along one 30 edge of the slot 11 to release the projections 17 from the tongues 9 and pulling downwardly. The 35 formation of 20 tongues and corrugations provides for 20 possible positions of the shell 10 in the cap 5 to procure so-called universal connection between the cap and shell, in order to locate the key slot in any desirable position with respect to the cap.

I claim:

1. In an electric light socket, a shell and cap, a longitudinally extending slot near the upper end of said shell, tongues substantially parallel 40 to the axis of the cap extending inwardly along the skirt of said cap having their free ends pointing upwardly, said tongues having cut metal edges adapted to contact with the edges of said slot when said shell and cap are assembled. 45

2. In an electric light socket, a shell and cap, a longitudinally extending slot extending from the upper end of said shell with its edges projecting outwardly, tongues substantially parallel 50 to the axis of the cap extending inwardly along the skirt of said cap having their free ends pointing upwardly, said tongues having cut metal edges adapted to contact with the edges of said slot when said cap and shell are assembled.

3. In an electric light socket, a shell and cap, 55 said shell being corrugated at its upper end, a longitudinally extending slot in the upper end of said shell, tongues substantially parallel to the axis of the cap extending inwardly along the skirt of said cap having their free ends pointing 60

upwardly, said tongues having cut metal edges adapted to contact with the edges of said slot when said shell and cap are assembled.

4. In an electric light socket, a shell and cap, 5 said shell having axially extending corrugations at its upper end, a slot in the upper end of said shell having its sides terminating at ridges of said corrugations, tongues extending inwardly along the skirt of said cap and having cut metal free edges along their sides adapted to contact with the edges of said slot when said shell and cap are assembled.

5. In an electric light socket, a shell and cap, 15 a longitudinally extending slot near the upper end of said shell, tongues substantially parallel to the axis of the cap extending inwardly along the skirt of said cap having their free ends pointing upwardly, said tongues having cut metal edges adapted to contact with the edges of said slot when said shell and cap are assembled, said slot being wide enough to accommodate a plurality of said tongues.

6. In an electric light socket, a shell and cap, 25 a key slot in said shell extending longitudinally of said shell and having the edges of its upper end extending outwardly, tongues extending inwardly along the skirt of said cap, the sides of said tongues being cut metal adapted to contact with the edges of said slot when said shell and cap are assembled.

7. In an electric light socket, a shell and cap, 35 a slot near the upper end of said shell, uniform tongues substantially parallel to the axis of the cap extending inwardly and upwardly along the skirt of said cap and projections on said shell adapted to contact with the free ends of some of said tongues when said shell and cap are assembled with other of said tongues contacting with the edges of said slot.

8. In an electric light socket, a shell and cap, 40 a slot near the upper end of said shell, uniform tongues extending inwardly and upwardly along the skirt of said cap and projections having cut metal ends on said shell adapted to contact with the free ends of some of said tongues when said shell and cap are assembled with other of said tongues contacting with the edges of said slot.

9. In an electric light socket, a shell and cap, 50 said shell being axially corrugated at its upper end, a slot in the upper end of said shell, equally spaced tongues substantially parallel to the axis of said cap extending inwardly along the skirt of said cap, the edges of said tongues being cut free and adapted to contact with the edges of said slot when said shell and cap are assembled, said tongues and corrugations being so spaced and located that said cap can be placed on said shell in a plurality of circumferential positions.

10. In an electric light socket, a shell and cap, 60 a slot near the upper end of said shell, a series of equally spaced uniform tongues with three cut metal edges extending inwardly and upwardly along the skirt of said cap and projections having cut metal ends on said shell adapted to contact with the free ends of some of said tongues when said shell and cap are assembled with other of said tongues contacting with the edges of said slot.

11. In an electric light socket, a shell and cap, 70 a plurality of inwardly projecting tongues on said cap having substantially parallel sides and having cut metal at their sides and at their inner ends, cut metal on said shell to engage with cut metal at the ends of said tongues to retain said shell and cap in assembled position, and cut

metal on said shell to engage with the sides of other of said tongues to prevent relative rotation between said cap and shell.

12. In an electric light socket, a shell and cap, 5 a plurality of similar, equally spaced inwardly projecting tongues on said cap having substantially parallel sides and having cut metal at their sides and at their inner ends, cut metal on said shell to engage with cut metal at the ends of said tongues to retain said shell and cap in assembled position, and cut metal on said shell to engage with the sides of other of said tongues to prevent relative rotation between said cap and shell.

13. In an electric light socket, a shell and cap, 15 a plurality of inwardly projecting tongues on said cap having cut metal at their sides and at their inner ends, cut metal on said shell to engage with cut metal at the ends of said tongues to retain said shell and cap in assembled position, and cut metal on said shell to engage with the sides of other of said tongues to prevent relative rotation 20 between said cap and shell, said cut metal on said shell extending outwardly farther than adjacent portions of said shell.

14. In an electric light socket, a shell and cap, 25 a plurality of inwardly projecting tongues on said cap having cut metal at their sides and at their inner ends, cut metal on said shell to engage with cut metal at the ends of said tongues to retain said shell and cap in assembled position, and cut 30 metal on said shell to engage with the sides of other of said tongues to prevent relative rotation between said cap and shell, said last named cut metal of said shell being located at the sides 35 of a slot in said shell.

15. In an electric light socket comprising a 40 cap and shell, a cap having a series of equally spaced tongues thereon, and means on said shell whereby some of said tongues prevent separation of said cap and shell and others of which prevent rotation between said cap and shell.

16. A cap for an electric light socket having an opening for electric wires therethrough and having a series of equally spaced tongues on the skirt thereof, the lengths of said tongues being 45 longitudinal of the axis of said cap.

17. A cap for an electric light socket having an opening for electric wires therethrough and having a series of equally spaced tongues on the skirt thereof, the ends of said tongues being parallel to the edge of said cap and the sides thereof being perpendicular to said ends.

18. A cap for an electric light socket having an opening for electric wires therethrough and having a series of equally spaced substantially 55 rectangularly shaped tongues on the skirt thereof, the ends and sides of said tongues being formed of cut metal.

19. A cap for an electric light socket having an opening for electric wires therethrough and having a series of equally spaced tongues on the skirt thereof of substantially the same thickness as the metal of said cap, the ends of said tongues being parallel to the edge of said cap and the sides thereof being perpendicular to said ends.

20. In an electric light socket comprising a cap and shell, a cap having a series of equally spaced tongues thereon, and means on said shell whereby some of said tongues prevent separation of said cap and shell and others of which prevent rotation between said cap and shell, said means comprising cut metal edges of said shell parallel to its axis and cut metal edges of said shell in a plane perpendicular to its axis.
